CLAIM

The ornamental design for an engine incorporating an overhead valve cover, as shown and described.

DESCRIPTION

FIG. 1 is a front-right top perspective view of an engine incorporating an overhead valve cover according to the new design;

FIG. 2 is a close-up view of area II of FIG. 2;

FIG. 3 is a front-left top perspective view thereof;

FIG. 4 is a close-up view of area IV of FIG. 4;

FIG. 5 is a rear-left top perspective view thereof;

FIG. 6 is a rear-right top perspective view thereof;

FIG. 7 is a front-right bottom perspective view thereof;

FIG. 8 is a close-up view of area VIII of FIG. 7;

FIG. 9 is a front-left bottom perspective view thereof;

FIG. 10 is a close-up view of area X of FIG. 9;

FIG. 11 is a rear-left bottom perspective view thereof;

FIG. 12 is a rear-right bottom perspective view thereof;

FIG. 13 is a front plan view thereof;

FIG. 14 is a close-up view of area XIV of FIG. 13;

FIG. 15 is a rear plan view thereof;

FIG. 16 is a right-side plan view thereof;

FIG. 17 is a left-side plan view thereof;

FIG. 18 is a top plan view thereof; and,

FIG. 19 is a bottom plan view thereof.

The dashed lines of equal length in FIGS. 1-19 are for environmental purposes only and form no part of the claimed design. The dashed lines of unequal length in FIGS. 1-4, 7-10, 13, and 14 represent an unclaimed boundary.

1 Claim, 19 Drawing Sheets
